UNITED STATES PATENT OFFICE.

MARIO ZUCCATO, OF PHILADELPHIA, PENNSYLVANIA, ASSIGNOR TO BACCELLIERI BROS., OF PHILADELPHIA, PENNSYLVANIA.

CORKING MACHINE.

Application filed June 10, 1921, Serial No. 476,545. Renewed December 10, 1924.

To all whom it may concern:

Be it known that I, MARIO ZUCCATO, a subject of the King of Italy, residing at Philadelphia, in the county of Philadelphia and 5 State of Pennsylvania, have invented new and useful Improvements in Corking Machines, of which the following is a specification.

This invention relates to corking machines 10 and it has more particular reference to manually actuated machines for corking bottles, the primary object being to provide a simple and efficient device whereby corks may be expeditiously inserted into the necks of 15 bottles and the like.

Another object of this invention is to provide a simple and reliable machine of the nature referred to which may be readily clamped on the edge of a table or other appropriate structure.

Still further the invention has for an object the provision of a corking machine which comprises but few and simple parts that are easily assembled and when assembled are not liable to get out of order.

With the foregoing and other objects in view as will later on be more apparent the invention consists essentially in the novel construction, combination and arrangement 30 of parts hereinafter fully described and more particularly pointed out by the appended claims.

In the further disclosure of the invention reference is to be had to the accompanying 35 drawings constituting a part of this specification, and in which like characters of reference designate the same parts in both the views.

Figure 1 is a broken perspective view of 40 my improved corking machine with the operating lever shown raised or out of use, and,

Figure 2 is a similar perspective view but showing the part in the operative position.

Referring to the drawings the numeral 45 10 designates a substantially rectangular box or casing which is provided with a depending bracket 11 and thumb screw 12 by means of which the device may be readily clamped on to a table or in other convenient positions. 50 Extending laterally from one end of the aforesaid box 10 is a forked arm 13 in which is pivoted by a pin 14 the operating lever 15. This operating lever as will be seen from the drawings is of somewhat zig-zag 55 pattern and it has appropriately attached

thereto at 16 a rod or plunger 17 provided with a head 18 that serves in use as later on explained to force the cork into the neck of a bottle. Slidably mounted within the aforesaid box 10 is a somewhat cruciform 60 member 19 which is provided with obliquely inclined ribs 20 which guide the said member 19 to and fro in the box 10 and it will be seen on an examination of Figure 1 that there is pivoted to this cruciform member 65 by a lug 21 a connecting rod 22 in turn pivotally attached at 23 to the aforesaid operating lever 15. It is also to be noted that the aforesaid cruciform member 19 is provided with a vertically grooved portion or jaw 24 70 which as later on explained is adapted to co-operate with a corresponding jaw 25 when gripping a cork, said jaw 25 in turn being formed integral with or attached to the aforesaid box 10.

Vertically upstanding within the box 10 is a pin 26 which limits the movement of the cruciform member in one direction, whilst the end of the box 10 limits it in the reverse direction. Hingedly mounted in one corner 80 of the box 10 and under the action of a retractile spring 27 is a hinged member 28 which is provided with a lip portion 29 which in use rides over the face 30 of the juxtaposed part of the cruciform member 85 19 and serves to compress the cork compactly between the opposed jaws 24-25. Projecting downwardly from the underside of the box 10 and axially central with the aforesaid jaws 24-25 when collapsed or 90 moved toward each other is a depending tubular nozzle 31 through which the cork compressed as above set forth is forced by engagement of the headed part 18 of the rod 17 thereon and as will be clearly understood 95 on an examination of the views. A bottle neck is indicated on the drawings in dotted lines by the numeral 32 and it will be readily understood that the bottle can be held by one hand beneath the nozzle 31 when it is desired 100 to cork same. A plunger device 33 under the action of a compression spring 34 is housed within the aforesaid box 10 and is provided at its lower part with a crescent-shaped member 35 for engagement with the 105 neck of the bottle, and it will be noted that when the operating lever 15 is forced downwardly as shown in Figure 2 that it contacts with this plunger device 34 and thereby prevents the cork from being forced too far 110

into the neck of the bottle. A lid or cover 36 is appropriately secured on the flanged top of the box 10 so that the parts are protected from damage and the like.

5 Upon throwing the lever 15 from the position shown in Figure 1 to that shown in Figure 2, the member 19 is moved to the right by link 22, the jaw 24 passing in front of pin 26 and the wall 30 passing in rear of 10 said pin until the latter occupies a position inside the member 19 and limits movement thereof by coming in contact with the transverse wall thereof. In the meantime jaws 24, 25 and plate 29 have compressed the cork 15 and plunger 17 has forced the cork into the bottle, also member 35 has been operated to strip the bottle from the machine.

From the foregoing description and an examination of the drawings the operation 20 and effectiveness of my improved corking machine will be clearly apparent without further description, and whilst I have shown and described the best form of my invention at present known to me, the same is 25 susceptible of various detailed changes and other arrangement of the several parts without departing from the spirit and essential features thereof and it is hereby intended to include all such reasonable modifications 30 as fairly fall within the scope of the appended claims.

Having described my invention what I claim as new, and desire to secure by Letters Patent is:

35 1. A bottle corking machine comprising a rectangular body having a depending cy-

lindrical cork guide thereon, a rigid cork forming jaw within said body, a slide within said body, diagonally extending guiding arms on said slide engaging the interior of 40 the body for guiding movement of the slide, said slide comprising spaced substantially parallel portions, a cork forming jaw upon one of said parallel portions, a cam on the other parallel portion, and a pivotally 45 mounted spring actuated cork compressing member carried by said body and adapted to be moved into cork compressing position by said cam upon movement of the slide into bottle corking position.

2. A bottle corking machine comprising a rectangular body having a depending cylindrical cork guide thereon, a rigid cork forming jaw within said body, a slide within said body, diagonally extending guiding arms on said slide engaging the interior 50 of the body for guiding movement of the slide, said slide comprising spaced substantially parallel portions, a cork forming jaw upon one of said parallel portions, a cam on the other parallel portion, a pivotally 55 mounted spring actuated cork compressing member carried by said body and adapted to be moved into cork compressing position by said cam upon movement of the slide into 60 bottle corking position, a hand lever pivotally carried by said body, a cork engaging plunger pivotally carried by said hand lever, and a coupling rod pivotally connecting the hand lever and slide.

In testimony whereof I affix my signature.
MARIO ZUCCATO.
